UNITED STATES PATENT OFFICE

HERBERT A. ANDERSON, OF CHICAGO, ILLINOIS, ASSIGNOR TO AMERICAN REENFORCED PAPER COMPANY, OF ATTLEBORO, MASSACHUSETTS, A CORPORATION OF MASSACHUSETTS

REENFORCED BUILDING PAPER

Application filed November 26, 1930. Serial No. 498,267.

This invention relates to a novel form of reenforced paper adapted for use as a building or wrapping paper and for other purposes.

5 Two types of reenforced paper are now on the market; in one of these types the paper is reenforced by such materials as wire or unspun fibres of long staple that are no more elastic than the paper itself, and although 10 these reenforcing elements are stronger than the paper, both give way or rupture simultaneously when subjected to a breaking strain; in the second type the paper is reenforced by spun strands of cotton, linen, jute, 15 etc. or by a woven fabric formed of spun fibres, and although such reenforcing materials are stronger than the paper, they are more elastic due to the twists in the reenforcing yarn or twine, and as a result these 20 twisted reenforcing elements will stretch under tension and permit the paper to rupture.

The present invention is directed to a third and new type of reenforced paper which is 25 capable of stretching to a substantial degree without rupturing, and is formed by adhesively securing reenforcing elements in a straightened condition between sheets of paper that have previously been craped, 30 crimped or crinkled, so that the paper may stretch under tension without rupturing. As a result of this new construction an elastic or stretchable reenforced paper is produced which is well adapted for various uses where 35 this elastic condition is desirable to prevent the paper from rupturing.

The reenforcing material may be either spun or unspun fibres or a reenforcing sheet 40 which is not readily ruptured, and very good results are secured through the employment of unspun fibres of long staple as the reenforcing elements. The reenforcing material is preferably secured between the sheets of 45 paper by a waterproof adhesive such as tar or black asphaltum to render the paper moisture-proof.

A stretchable, reenforced, waterproof paper constructed in accordance with the present invention may be subjected to a strain 50 that is sufficient to break some of the reen-

forcing fibres without necessarily causing the craped or crinkled paper to rupture or lose its water-proof quality.

While the elastic reenforced paper of the present invention constitutes a cheap water-proof covering that may be well employed as a wrapper for bales, bundles and packages, and in the construction of bags, where additional strength over ordinary paper and a certain amount of give is required to prevent the paper from rupturing, it is particularly well adapted for use as a building paper which will not rupture or pull loose from its securing means under the contraction and expansion of the paper, due to weather 55 changes.

In employing building paper heretofore, in building constructions, much difficulty has been experienced when the paper is exposed to the weather, due to the tendency of the 60 paper to shrink under the action of the sun and rain, and pull loose from the nails or other means employed to fasten the paper in place. This shrinking action of the paper is particularly noticeable when a multiply 65 building paper is used having a waterproof coating between the sheets of paper, since while the inner sheet of paper may be kept dry by the coating material, it is acted upon by the repeated shrinking pull of the outer 70 sheet of paper, without expanding with the outer sheet to relieve its tension.

These difficulties are overcome through the employment of the reenforced paper of the present invention, as a building paper since 75 the face of the multiply paper exposed to the weather may contract and expand freely without rupturing or imparting its shrinking action to the underlying reenforcing material or inner sheet of paper. In this manner the 80 tendency of building paper to shrink and pull loose from its securing means under the action of the weather is entirely overcome.

The above and other features of the invention will be further understood from the following description when read in connection with the accompanying drawing, wherein:

Fig. 1 is a perspective view of a piece of multiply reenforced paper constructed in accordance with the present invention, the 100

sheets of paper being partly rolled back to show the reenforcing fibres;

Fig. 2 is a perspective view showing the paper of Fig. 1 as secured to a supporting structure indicated in dotted lines; and

Fig. 3 is a sectional view of a modified form of the reenforced stretchable paper of the present invention.

In the embodiment of the invention illustrated in Figs. 1 and 2 of the drawing, the multiply reenforced paper consists of the two sheets of paper 10 and 11, each of which is crimped, crinkled or given a crape construction throughout its area as shown. This is done to render the paper elastic or capable of stretching. In many cases the paper need be crimped or crinkled in only one direction to render it sufficiently elastic to secure the desired results, since if the crinkles or creases extend transversely of the paper, as shown in the drawing, the paper will be rendered elastic to a substantial degree in the direction of its length and will also be rendered elastic transversely to a slight degree. The paper, however, may be provided with crinkles or creases extending both longitudinally and transversely when it is desired to secure a paper that is capable of stretching to a substantial degree both longitudinally and transversely.

While, as above stated, various reenforcing materials may be used between the sheets of paper 10 and 11 to impart the desired strength to the composite paper, excellent results are secured through the employment of relatively long unspun fibres, such as sisal. The paper is therefore shown as reenforced by one set of straightened unspun fibres 12 extending longitudinally of the paper and another set of straightened unspun fibres 13 extending transversely of the paper. It is not always essential however, to reenforce the paper both longitudinally and transversely.

The adhesive employed should serve to firmly secure the reenforcing fibres and the two sheets of paper together so that the fibres will materially increase the strength of the paper and while the adhesive employed may be non-waterproof, a waterproof adhesive such as black asphaltum is usually desirable to prevent the moisture that reaches one sheet of paper from penetrating through to the second sheet of paper or from decreasing the gripping action of the adhesive.

When multiply building paper having the construction employed heretofore is secured to a building in an unprotected condition, it is found that the multiply paper tends to shrink repeatedly as its outer face becomes wet from time to time (due to rain or dampness) and dries out, and that this shrinking action causes the marginal portions of the building paper to pull loose from the nails or other means for holding it in place upon the building.

By constructing multiply paper in accord-

ance with the present invention, so that the outer sheet of paper which is exposed to the weather is crimped or crinkled, this outer sheet may contract and expand freely without rupturing or imparting its contracting action to the underlying reenforcing material. It will therefore be seen that the stretchable reenforced paper of the present invention forms an excellent building paper and that when the same is secured by nails or the like 14 to a portion of a building such as the boards 15 supported by beams 16, the overall dimension of the building paper will not be reduced by the contracting action of the outer or exposed sheet thereof, and as a result the paper will be permanently held in place by the securing means 14 and will not pull loose as heretofore.

When the paper of the present invention is to be used as a building paper, it may be sufficient to crape or crimp only the outer or exposed sheet of paper, since the inner sheet of paper which is not exposed to the rain and sun is not likely to shrink sufficiently to cause the multiply sheet of building paper to pull loose from its securing means, but if only one face of the reenforced paper is crimped care should be exercised to see that this and not the smooth uncrimped face of the paper is exposed to the weather.

The construction shown in Fig. 3 differs from the construction of Figs. 1 and 2 in that while the upper sheet 10 of the construction of Fig. 3 is crape or crimped, the lower sheet 17 is a smooth straight sheet of paper. The reenforcing fibres 12 and 13 of Fig. 3 may be the same as in Figs. 1 and 2.

It will be understood from the foregoing that the crinkles in a crape or crimped sheet of paper, not only render it elastic so that it may stretch without tearing, but also decrease the gripping action of the adhesive upon the sheet of paper at the raised portion of the crinkles, to thereby facilitate the contraction and expansion of this sheet of paper under different weather conditions relative to the reenforcing fibres.

The stretchable reenforced paper of the present invention therefore forms an excellent building paper that will stay in place upon exposure to the weather over a long period of time, and is also well adapted for use as a wrapping paper and for other purposes where a strong and stretchable waterproof material is desired.

What is claimed is:—

1. As an improved article of manufacture, a multi-ply, waterproof, building paper which will not shrink appreciably when exposed in a stretched condition to varying weather conditions, comprising a composite fabric formed of two sheets of paper crape or crimped to render them elastic or capable of stretching, and provided with unspun reenforcing fibres secured by a waterproof ad-

hesive in a straightened condition between the sheets so that the fibres extend both longitudinally and transversely of the sheets and arranged so that the craped or crimped sheet 5 exposed to the weather may contract and expand freely under the action of the weather while the reenforcing fibres maintain the overall dimension of the composite fabric substantially constant.

10 2. As an improved article of manufacture, a multi-ply, waterproof building paper which will not shrink appreciably when exposed in a stretched condition to varying weather conditions, comprising a composite 15 fabric formed of two sheets of paper craped or crimped to render them elastic or capable of stretching, and provided with unspun re-enforcing fibres secured by a waterproof adhesive in a straightened condition between 20 the sheets so that the craped or crimped sheet exposed to the weather may contract and expand freely under the action of the weather while the reenforcing fibres maintain the overall dimension of the composite fabric 25 substantially constant.

3. As an improved article of manufacture, a multi-ply, waterproof building paper which will not shrink appreciably when exposed in a stretched condition to varying weather 30 conditions, comprising a composite fabric formed of two sheets of paper one of which is craped or crimped to render it elastic or capable of stretching, and provided with re-enforcing strands secured by a waterproof 35 adhesive in a straightened condition between the sheets of paper so that the craped or crimped sheet when exposed to the weather may contract and expand freely under the action of the weather while the reenforcing 40 strands maintain the overall dimension of the composite fabric substantially constant.

In testimony whereof, I have signed my name to this specification.

HERBERT A. ANDERSON.
